United States Patent Office

Des. 230,312
Patented Feb. 5, 1974

230,312

ELECTROSTATIC COPIER

Richard H. Penny, New York, N.Y., assignor to Sperry
Rand Corporation, New York, N.Y.

Filed Sept. 25, 1972, Ser. No. 291,662

Term of patent 14 years

Int. Cl. D16—03

U.S. Cl. D61—1 Q

FIG. 1.

FIG. 6

FIG. 3.

FIG. 2.

FIG. 4.

FIG. 5.

FIG. 1 is a front perspective view of an electrostatic copier showing my new design;

FIG. 2 is a rear elevational view thereof;

FIG. 3 is a top-plan view thereof with the receiving trays in an operative position;

FIG. 4 is a front elevational view of FIG. 3;

FIG. 5 is a right-side elevational view thereof;

FIG. 6 is a left-side elevational view thereof.

I claim:

The ornamental design for an electrostatic copier, substantially as shown and described.
